UNITED STATES PATENT OFFICE.

WALTER LYTTON AND JOSHUA TEDFORD, OF CHICAGO, ILLINOIS; SAID TEDFORD
ASSIGNOR TO SAID LYTTON.

DELIVERY-TRUCK.

1,082,164.

Specification of Letters Patent. Patented Dec. 23, 1913.

Application filed January 8, 1912. Serial No. 670,114.

To all whom it may concern:

Be it known that we, WALTER LYTTON and JOSHUA TEDFORD, citizens of the United States, and residents of Chicago, county of Cook, and State of Illinois, have invented 5 certain new and useful Improvements in Delivery-Trucks, of which the following is a specification, and which are illustrated in the accompanying drawings, forming a part 10 thereof.

The invention relates to delivery trucks and particularly to those used for the conveyance of a large number of relatively small parcels desired to be separately delivered at different places along the route traversed by the truck.

The objects of the invention are to facilitate the loading of conveyances of this character and to render the packages more 20 readily accessible therein.

To this end the invention contemplates a conveyance having its body divided into suitable compartments all of which are accessible from one end of the body. Usually 25 these compartments will be contained within a crate or case adapted to be removed from the body of the conveyance whereby they may be filled when the crate is so removed and the loading of the truck affected by re- 30 turning the filled crate into the body.

In the accompanying drawings Figure 1 is a central longitudinal sectional view showing details of a delivery truck embodying the features of improvement provided 35 by the invention. Fig. 2 is a plan view of the crate shown within the body of the delivery truck illustrated in Fig. 1. Fig. 3 is an end view of the crate showing details of the truck in cross section. Fig. 4 is a detail perspective view illustrating a form of latch which may be used for securing the crate within the body of the truck. Fig. 5 is a detail plan view illustrating a form of hinged connector which may be used for 45 uniting the parts of the crate illustrated in Figs. 1, 2 and 3. Fig. 6 is a central longitudinal sectional view showing a modified form of crate, and Fig. 7 is a plan view of the crate shown in Fig. 6.

50 The body of a delivery conveyance is shown at 10 in the drawings. Details of the running gear of the conveyance are shown at 11. The body 10 is illustrated as being of the closed type and has a floor 12 and a

hood or roof 13. Doors 14 extending from 55 the floor 12 to the roof 13 are used for closing the rear end of the body and a seat 15 extends across the body adjacent its front end. The particular form of the invention illustrated provides for the loading of the 60 body of the conveyance through the doors 14 at the rear end and permits all of the parcels constituting the load to be reached by a person occupying the seat 15 whereby 65 their delivery may be effected without entering the body 10 from the rear.

As shown, a crate generally designated 16 is removably held within the body 10 in rear of the seat 15. To facilitate the introduction and removal of this crate through 70 the doors 14, it is equipped with carrying wheels 17 which run upon the floor 12 of the body 10. If desired the floor 12 may be provided with rails 18 adapted for engagement by the carrying wheels 17 of the crate 75 16. By making these rails of the grooved form shown in Fig. 3, lateral displacement of the crate within the body is prevented. For preventing longitudinal movement of the crate 16 within the body 10 of the conveyance during the travel of the conveyance, a latch 19 is employed for securing the crate to the floor 12. As shown, the latch 19 is hingedly connected to the floor 12 at 20 and it is provided with an aperture 85 21 at its free end for engaging an appurtenance of the crate 16, as the staple 22. The free end of the latch 19 is firmly connected to the staple 22 by any convenient means, as for example, the padlock shown 90 at 23.

Most desirably the crate 16 has slatted side walls 24, 25 but is open at both ends, as indicated at 26, 27, Fig. 1. In practice the crate 16 will be filled when it is removed 95 from the body 10 of the conveyance whereby the conveyance is loaded by simply introducing the filled crate into the body 10 through the doors 14 and securing the same in place with the latch 19. When this practice is followed the conveyance may be used for another purpose during the filling of the crate, as for example, the delivery of parcels contained in another similar crate (not shown).

100 In order that all of the parcels contained within the crate 16 may be accessible to a person occupying the seat 15 by simply 105

reaching over the back of the seat, the crate is divided into a plurality of compartments and provision is made for moving the contents of those compartments which are located adjacent the rear end of the crate toward its forward end when the contents of the last mentioned part of the crate have been discharged. As shown in Figs. 1, 2 and 3 of the drawings the body of the crate 10 is horizontally divided by oppositely inclined partitions or shelves 28 and 29. One of these shelves, as 28, is made movable to discharge the parcels held thereon toward the forward end of the crate, as by being 15 hingedly connected at its forward end to the rear end of the shelf 29.

If desired, that part of the crate above the shelves 28 and 29 may be transversely divided at the midlength of the crate by a 20 swinging gate 30. As shown, the gate 30 and movable shelf 28 are both connected to the shelf 29 by a plurality of hinges 31. One of these hinges is shown in detail in Fig. 5 of the drawings. It comprises a plurality of leaves or parts, as 33, 34, 35 and 36, all mounted upon a common pintle 32. The two outer leaves or parts of the hinge 31, as 33, 34, are secured to the stationary shelf 29. One of the intermediate parts of 25 the hinge, as 35, is secured to the movable partition 28 and a fourth part of the hinge, as 36, is secured to the gate 30. Spring latches 37 and 38 secured to the opposite side walls 24 and 25 of the crate 16 and engageable with the gate 30 at its opposite ends, serve to releasably hold the gate in the upright central position illustrated by full lines in Figs. 1, 2 and 3 of the drawings. In practice, the parcels held by the shelf 29 in 30 front of the gate 30 will first be discharged and the gate 30 will then be turned down upon the shelf 29, as indicated by the dotted line on Fig. 1.

In order that the packages supported by 45 the shelf 28 in rear of the gate 30 may then be accessible to a person occupying the seat 15, provision is made for raising the shelf 28 to discharge its load upon the gate 30 as it rests upon the partition 29 whereby 50 the shelf 28 serves in effect, as a movable follower adapted to carry its load forwardly between the side walls 24, 25 of the crate. As shown, the free end of the shelf 28 is normally supported by brackets 39 and 40, 55 one of which is secured to each of the side members 24 and 25 of the crate. For raising the shelf 28 a cord 41 attached to the free end of the shelf, as at 42, is used. This cord preferably extends to a position which 60 is conveniently accessible to a person occupying the seat 15, as by being passed over guide pulleys 43 and 44 secured to the underside of the roof 13. If desired provision may also be made for moving packages contained in the lower part of the crate below

the shelf 28 forwardly when those which have been held in the forward part of the crate below the shelf 29 have been discharged. As shown, a box 45, slidably mounted upon the floor of the crate 16 is 70 used for this purpose. This box is preferably substantially equal in length to half the length of the crate 16 and is of sufficient height and width to fill the crate 16 from side to side below the shelf 28. The box 45 will initially be located adjacent the rear end of the crate 16 thereby providing a space within the crate beneath the shelf 29 for receiving packages which are to be discharged in advance of those held within the 80 box. When all of the packages located in front of the box 45 have been discharged, this box will be moved forwardly by sliding it upon the floor of the crate 16 to bring the packages contained therein within easy 85 reach of a person occupying the seat 15.

The form of construction illustrated in Figs. 1, 2, and 3 of the drawings provides four divisions or compartments within which packages may be retained. A convenient method of using the device is to load the crate 16 when it has been removed from the body 10 of the conveyance, smaller parcels being placed upon the shelves 28 and 29 and larger parcels in the space below the 90 shelf 29 and in the box 45. Usually the parcels desired to be first discharged will be located in front of the midlength of the crate, the smaller parcels being upon the partition 29 in front of the gate 30 and the 95 large parcels below the partition 29 in front of the space occupied by the box 45. The parcels desired to be discharged during the latter part of the travel of the conveyance upon a predetermined route will be placed in rear of the midlength of the crate, the smaller parcels upon the shelf 28 in rear of the gate 30 and the larger parcels within the box 45. When the crate 16 has been 100 placed within the body 10 of the conveyance and the doors 14 closed, the parcels to be delivered may be selected from the crate 16 by a person occupying the seat 15 during the travel of the conveyance. Deliveries of the parcels may accordingly be made immediately upon the arrival of the conveyance at the place to which the parcels are directed. When the parcels which were originally located in front of the midlength of the crate 16 have been discharged, the gate 30 will be 110 swung forwardly and the partition 28 raised to discharge its load upon the upper side of the gate as it rests upon the shelf 29. At the same time the box 45 will be drawn forwardly to bring it into an accessible position 115 beneath the shelf 29. The entire contents of the crate are thereby rendered accessible from one end of the conveyance whereby in making deliveries it is unnecessary to enter the body 10 from the rear.

Figs. 6 and 7 of the drawing show a crate 46 which may be used within the body 10 of the conveyance in lieu of the crate 16 shown in Figs. 1, 2 and 3. The crate 46 is 5 preferably open at one end as indicated at 47, Fig. 6, and it is divided into upper and lower compartments 48, 49 by a horizontal shelf 50. This shelf preferably extends the entire length of the crate. Each of the compartments 48, 49 is closed at the rear end of the 10 crate by a movable follower, as 51, 52. These followers are adapted to be drawn forwardly in their respective compartments as the contents of the compartments adjacent 15 the open end of the crate are discharged. To this end each of the followers 51, 52 is secured to one end of a traveling apron, as 53, 54 which extends forwardly therefrom over the floor of the corresponding compartment to the open end of the 20 crate where it turns over a guide roller, as 55, 56 and is wound upon a drum, as 57, 58. Each of the drums 57, 58 is operated by a hand wheel 59 located at one side of the 25 crate.

In the use of the crate 46 illustrated in Figs. 6 and 7 of the drawings, the parcels desired to be first discharged will be placed in the compartments 48 and 49 adjacent the 30 open end of the crate, the smaller parcels being placed in the compartment 48 and larger parcels in the compartment 49. Parcels desired to be discharged during the latter part of the travel of the conveyance 35 will be located adjacent the followers 51 and 52. As the parcels located adjacent the open end of the crate 46 are discharged, the followers 51 and 52 will be drawn forwardly by turning the drums 57 and 58. By this 40 means all of the parcels contained within the crate are rendered accessible from its open end, as in the form of construction illustrated in Figs. 1, 2 and 3.

We claim as our invention—

45 1. In combination, a delivery truck having a body, a crate removably held within the body of the truck and substantially filling the same, and a follower movable through the crate toward one end of the body of the truck.

2. In combination, a delivery truck having a body, a crate removably held within the body of the truck and substantially filling the same, a follower movable through 50 the crate toward one end of the body of the truck, and means for manually actuating the follower said means being located at the end of the body of the truck toward which the follower is movable.

60 3. In combination, a delivery truck having a body, a swinging gate transversely di-

viding the body and a forwardly movable follower in rear of the gate.

4. In combination, a delivery truck having a body, and a pair of shelves extending 65 in opposite directions from a transverse line within the body, one of the said shelves being fixed in the body and the other shelf being movable to deliver its load upon the fixed shelf. 70

5. In combination, a delivery truck having a body, a pair of shelves inclined upwardly in opposite directions from a transverse line within the body, one of the said shelves being fixed and the other movable, 75 the adjacent edges of the two shelves being hingedly connected whereby the movable shelf may be raised to discharge its load upon the fixed shelf, and a transverse swinging gate dividing the space embraced by the 80 shelves.

6. In combination, a delivery truck having a body, a crate removably held within the body of the truck and substantially filling the same; a swinging gate transversely 85 dividing the crate and a forwardly movable carrier within the crate in rear of the gate.

7. In combination, a delivery truck having a body, a crate removably held within the body of the truck and substantially filling 90 the same; and a pair of shelves extending in opposite directions from a transverse line within the crate, one of the said shelves being fixed in the crate and the other shelf being movable to deliver its load upon the 95 fixed shelf.

8. In combination, a delivery truck having a body, a crate removably held within the body of the truck and substantially filling the same, a pair of shelves extending in 100 opposite directions from a transverse line within the crate, one of said shelves being fixed in the crate and the other shelf being movable to deliver its load upon the fixed shelf, and a transverse swinging gate dividing the space above the shelves. 105

9. In combination, a delivery truck having a body, a crate removably held within the body of the truck and substantially filling the same, a horizontal partition extending throughout the length and width of the crate and dividing the same into upper and lower compartments, and a follower movable through each of the said compartments of the crate toward one end of the body of 110 the truck. 115
